UNITED STATES PATENT OFFICE.

OTTO B. LINDQUIST, OF TARENTUM, PENNSYLVANIA, ASSIGNOR TO HARRY E. SHELDON,
OF PITTSBURGH, PENNSYLVANIA.

CORRUGATING APPARATUS.

1,211,460.

Specification of Letters Patent.

Patented Jan. 9, 1917.

Application filed May 27, 1914. Serial No. 841,258.

To all whom it may concern:

Be it known that I, OTTO B. LINDQUIST, a citizen of the United States, residing at Tarentum, in the county of Allegheny and State of Pennsylvania, have invented new and useful Improvements in Corrugating Apparatus, of which the following is a specification.

My invention relates to apparatus for manufacturing steel or other metal plates into corrugated plates each having a corrugated portion surrounded by a plain, smooth, or uncorrugated border.

It is the object of my invention to provide a suitable set of rolls and mechanism coöperative therewith for forming such corrugated plates as I have described above. I may form such plates from plates having the required length for a single finished plate, or I may form a series of sets of corrugations in a long plate and cut the latter into sections between the sets of corrugations.

It is also the object of my invention to provide on each side of the rolls suitable mechanism for preventing the plates from buckling and curving.

Other objects will appear hereinafter.

Referring to the accompanying drawings, Figure 1 is a longitudinal vertical section 30 of an apparatus involving my invention; Fig. 2, a plan of Fig. 1; Fig. 3, a plan of a portion of a sheet after its treatment by my invention; Fig. 4, a plan of a single corrugated plate which may be formed by my invention or may be a section formed by cutting the plate shown on Fig. 3 on the dotted lines thereon; and Fig. 5, a section of Fig. 3 on the line V—V.

On the drawings, 1 and 2 represent a pair 40 of horizontal rolls, one vertical over the other. These rolls are mounted in the housings 3, the upper roll being adjustable by means of the screws 4 in a manner well known. The rolls are caused to rotate at the same speed by means of the usual spur gearing connected to the necks of the rolls, one of the gear wheels 5 being shown on Fig. 2. The upper roll 1 is cylindrical and provided with a number of parallel grooves 6 in its periphery, these grooves being interrupted from the point 7 to the point 8 by leaving the roll between these points in its normal condition, that is the surface of the roll 1 between the points 7 and 8 is a part of the cylinder in which the said grooves have been

formed. The lower roll 2 is also cylindrical but has thereon a series of ribs 9 corresponding in position, cross-section and length to the same characteristics of the grooves 6 with which the said ribs coöperate to form corrugations in sheets of metal fed between the rolls. The surface of the roll 2 is left normal between the points 10 and 11, which correspond in position to the points 7 and 8 on the roll 1. The roll 1 has its normal surface preserved between the points 7 and 8, and the roll 2 has its normal surface preserved between the corresponding points 10 and 11, so that portions of the plates fed between the rolls will not be corrugated.

On the feeding-in or entrance side of the rolls 1 and 2 I mount the two horizontal rollers 12 and 13 having their pass in line with the pass between the rolls 1 and 2. I make one of these rollers yielding in order 75 to accommodate plates of different thicknesses. Inasmuch as I have shown the grooves on the upper roll 1 and the ribs on the lower roll 2, I have made the upper roller 12 non-adjustable in order to prevent 80 the plate from bending or warping upwardly by the pressure of the ribs 9 against the same. The lower roller 13 is shown yieldingly pressed upward by the coil-spring 14, its tension being regulated by the 85 screw 15. Between the rolls and the rollers I have placed the triangular guide-blocks 16, the lower one of which may be adjusted in any convenient manner.

On the discharge side of the rolls 1 and 2 90 I have shown the guide-blocks 18 having between them a guide passage in line with the passes between the rolls 1 and 2 and the rollers 12 and 13.

On the discharge side of the rolls 1 and 2 95 and beyond the guide-blocks 18 I arrange a number of pair of vertical rollers 19 and 20, the upper roller 20 of each pair being adjustable by means of the screws 21. Inasmuch as the ribs on the plates corrugated by 100 the rolls 1 and 2 have the corrugations formed in the upper surface thereof, I have made the rollers 19 plain cylinders and the upper rollers 20 with corrugations corresponding to the corrugations in the plates. 105 Preferably the rollers 19 and 20 will be driven by suitable gearing 22.

23 represents a metal plate which has been fed for some distance through the corrugating apparatus. It will be seen that as the 110

plate is fed between the rolls 1 and 2 ribs 24 will be pressed above the upper surface of the plate 23 for a distance corresponding to the length of the grooves 6 and the ribs 9. 5 At every revolution of the rolls series of parallel ribs 24 will be formed on the upper surface of the plate 23 and each set of corrugations 24 will be separated from each preceding or succeeding set of ribs by a plain 10 or flat portion 25. The ribs and grooves have their ends tapered as shown on the drawings in order to draw the metal more gradually from the surface of the plate 23 and to give the corrugations a better appearance. 15 A plate with a single set of corrugations 24 such as is shown in Fig. 4 may be formed with plain or flat portions 25 at each end. In case a long sheet in which several sets of corrugations 24 are to be made 20 is passed through the corrugating machine, the plain or flat portion 25 between the sets of corrugations will be severed, for example, on the lines 26 to form separate corrugated plates such as are shown on Fig. 4. The 25 surface of the rolls beyond the ribs and grooves are left normal or cylindrical so that the plate 23 will have its sides beyond the corrugations 24 flat or in its normal condition. By means of the normal ends of the 30 rolls and the normal surfaces between the points 7 and 8, and 10 and 11, the plates corrugated by the rolls will have a border or margin in the normal plane of the plate 23. I have shown the rolls 1 and 2 hollow, but 35 I do not desire to be limited to this feature. By making the rolls hollow they may be artificially cooled by causing air or water to flow through them, it being understood that the plates to be corrugated are brought to a

good heat such as will permit the corrugations to be drawn out of the plane of the plate without damage to the plate. The necks or trunnions of the rolls may have 40 axial openings 27 (only one being shown) through which air or water may be introduced into the same and led therefrom. Both rolls may be constructed exactly alike except that one has the ribs and the other the grooves; but I prefer to make the roll 2 with 45 hand holes 28 in its ends so that the nuts 29 may be turned on the bolts 30 which extend through the ribs and the wall of the roll. The heads of the bolts 30 are shaped to conform to the shape of the ribs and form a 50 part of the working surface thereof. Besides affording means for cooling the rolls or ribs and for giving access to the fastening devices for the ribs, the hollows in the rolls materially reduce their weight. 55

I claim—

The combination of a roll having ribs thereon, a second roll having grooves coöperating with the said ribs to form ribs on a metal plate fed between the rolls, the latter having opposed surfaces interrupting the 60 continuity of the said ribs and grooves on the rolls, and pairs of rollers between which the plate is fed from the rolls, the rollers which lie on the same side of the plate as the grooved roll having corrugations fitting the corrugations of the plate. 65

Signed at Brackenridge, Pa., this 23rd day of May, A. D. 1914.

OTTO B. LINDQUIST.
